UNITED STATES PATENT OFFICE

CARL H. FRINK, OF CLAYTON, NEW YORK

SNOWPLOW

Application filed May 1, 1929. Serial No. 359,547.

This invention relates to a snow leveling device adapted to be attached to the rear portion of a motor truck carrying at its front end a snow plow attachment of the class set forth 5 in my Patent No. 1,589,748, June 22, 1926, the main object being to widen the channel through the snow formed by the plow by leveling off the banks of snow thrown out by the plow blades as the machine proceeds 10 along the road and thereby to reduce the liability of drifting of the snow into the channel formed by the plow.

In other words, I have sought to greatly increase the width of the highway available 15 for traffic during or following more or less severe snow storms in one continuous operation of the truck along the highway without producing excessive load upon the motive power.

One of the specific objects is to locate the plow in front of the truck with its apex in the longitudinal center thereof and to mount 20 upon opposite sides of the same truck some distance to the rear of the plow a pair of leveling wings which may be raised and lowered as may be necessary or desirable according to the depth of the snow operated upon.

Another object is to permit the leveling wings to be elevated and folded close to opposite sides of the truck when not in use.

A further object is to provide means whereby the blades may automatically adjust themselves to obstructions along the highway without serious detriment to the machine or obstructions such as manhole plates, curbs and the like commonly used in cities and analogous districts.

Another object is to support the leveling blades in such manner that they may be folded and unfolded toward and from the adjacent sides of the truck.

Another object is to provide means whereby the blades may be adjusted vertically to different heights and to different angles relatively to a horizontal plane.

Other objects and uses relating to specific parts of the machine will be brought out in the following description.

In the drawings:

Figure 1 is a top plan of a motor truck

equipped with my invention in which the leveling wings are adjusted for use.

Figure 2 is an enlarged side elevation of the rear end of the truck and leveling wings mounted thereon showing also the means for raising and lowering the wings which are indicated by dotted lines in their elevated inoperative positions.

Figure 3 is an enlarged detail vertical sectional view taken in the plane of line 3-3, Figure 2.

Figures 4 and 5 are enlarged detail vertical sectional views taken respectively in the planes of lines 4-4 and 5-5, Figure 1.

In order that my invention may be clearly understood I have shown a portion of a motor vehicle comprising opposite lengthwise side bars or sills —1— of the chassis or frame upon which is mounted a motor 2, a cab 3, and a box or body 4, the parts 2, 3 and 4 being arranged in sequence from front to rear of the vehicle.

A snowplow 5 similar to that set forth in my patent previously referred to is detachably mounted on the front end of the chassis 75 of the vehicle to project forwardly therefrom and is provided at its front end with a substantially straight horizontal plow blade 6 and rearwardly diverging deflecting blades 7 arranged with their apex in the longitudinal center of the vehicle and their outer ends extended some distance beyond the sides of the vehicle, the plow blade 6 being disposed at substantially right angles to the longitudinal center of the machine to extend equal distances therefrom.

The means for attaching the plow to the front end of the machine and also the means for adjusting it vertically are similar to that set forth in my patent but obviously may be varied at will without departing from the spirit of the present invention.

A pair of leveling wings 8 are attached to the rear portion of the chassis just at the rear of the cab 3 or a considerable distance to the rear of the plow 5 in such manner that they may be moved laterally to different angles relatively to the longitudinal center of the chassis and also adjusted vertically to different heights as may be required to effect 100

a proper leveling of the snow ridges and widening of the channel in the snow formed by the plow 5.

The wings 8 are similar in construction and 5 elongated lengthwise of the vehicle so as to extend across the outer ends of the wheels —A— and beyond opposite ends of the body 4 and each comprises an outer sheet metal plate 9 reinforced at intervals throughout 10 its length by somewhat heavier straps 10 of bar steel or equivalent material to hold the sheet metal sections 9 against buckling and to resist the strains incidental to the impact of the sheet metal sections with the snow.

15 These sheet metal sections 9 and reinforcing straps 10 are preferably concavo-convex in cross section with their convex sides facing outwardly, the upper edge of the sheet metal section 9 being returned upwardly and rearwardly to form a reinforcing flange 11.

A scraper blade 12 of flat steel or equivalent metal is secured by bolts 13 to the lower forwardly projecting edge of the sheet metal section 9 and one of the reinforcing straps 10 25 to extend downwardly beyond the lower edge of the sheet metal section for engagement with the snow and ice closely adjacent the pavement.

The lower edges of the sheet metal section 30 9 are further reinforced by angle irons 14 applied to the inner faces thereof between the section 9 and the lower ends of the reinforcing strap 10 which, together with the reinforcing member 14 are clamped firmly in place by the 35 same bolts 13 which hold the scraper blades 12 in operative position. Each of the wings 8 is hingedly secured near its front end to a yoke 15 by means of a pivotal bolt 16, Figure 3, said yoke being arranged in a vertical 40 position and has its lower and upper ends provided with apertured flanges 17 in vertically spaced relation above and below the pivotal bolt 16 for receiving an upright pivotal rod or bar 18 which extends some distance above and below the upper and lower 45 ends of the yoke 15 and has its lower and upper ends mounted in apertured flanges 19 on an upright post 20.

This post is preferably made in the form 50 of an angle iron and is secured by a U-bolt 21 to the outer face of the adjacent sill 1 of the chassis, Figures 2 and 3.

That is, the upright posts 20 are rigidly secured to the chassis sills 1 and are each provided with the outwardly projecting flanges 19 which are arranged in vertically spaced relation to receive and support the lower and upper ends of the yoke-supporting rod or bar 18, each yoke 15 being slidable vertically 60 along its supporting rod or bar 18 between the flanges 19.

These flanges are preferably made in the form of angle irons which are riveted or otherwise secured to the outer faces of the posts 20 as shown more clearly in Figure 3.

Each of the posts 20 extends some distance above and below its supporting sill 1 while the flanges 19 thereon are spaced apart vertically a considerably greater distance than the length of the adjacent yoke 15 to allow 70 said yoke with the wing 8 thereon to be adjusted vertically for varying the distance of the lower edge of the scraper blade 12 from the pavement and thereby effecting a corresponding variation in the level of the snow 75 removed by the wings.

It is now clear that each wing has three distinct movements, first; a vertical rocking movement about the axis of the pivotal bolt 16 to vary the vertical angle of the wing, second; a vertical bodily movement along the upright guide rod 18 to vary the distance of the scraper blade 12 from the surface of the pavement and thereby to vary the level of the snow operated upon by the wing and; 80 third, a horizontal swinging movement about the axis of the guide rod 18 for varying the horizontal angle of the wing relatively to the longitudinal center of the chassis and thereby to vary the lateral deflection of the snow 85 and resultant widening of the available surface of the roadway for traffic purposes.

These several movements may also be utilized for folding and unfolding the wings toward and from the adjacent sides of the chassis and for the elevation of the wings some 90 distance from the pavement when not in use.

Each of the wings 8 is provided near its rear end with a reinforcing bar 22 which is similar to but somewhat longer vertically 100 than the reinforcing bar 10 due to the increased vertical height of the rear end of the wing, said reinforcing bar being made of steel or equivalent material and bolted or otherwise secured to the rear face of the adjacent portion of the sheet metal section 9, as 105 shown in Figure 4.

Each of the bars 22 is provided with a pair of inwardly projecting flanges 23 consisting of angle irons bolted or otherwise secured thereto and arranged in vertically spaced relation for receiving and supporting an upright post 24 having its lower and upper ends reduced at 25 and engaged in corresponding apertures in the flanges 23, the reduced portions or pintles 25 being free to turn in said apertures to compensate for varying adjustments of the wing.

The rear ends of the wings 8 are braced in their operative positions against undue inward movement by a pair of thrust bars 26, one for each wing, each bar having its outer end pivoted at 27 to the post 24 near the lower end thereof or just above the lower flange 23 and its front end flexibly connected by a 120 clevice 28 or equivalent attaching member to an angle iron 29 which is bolted or otherwise secured to the outer face of the adjacent sill 1 near the rear end thereof as shown in 125 Figures 1 and 4.

5 The clevice 28 is not only pivotally connected to the angle iron 29 but is also pivotally connected to a plate 30 on the inner end of the thrust bar 26, said plate 30 being provided with a series of apertures 31 in longitudinally spaced relation for receiving the adjacent end of the clevice 28 and thus permitting the corresponding wing 8 to be adjusted inwardly and outwardly to different 10 angles about the axis of its supporting rod 18.

10 The intermediate portion of each thrust bar is connected by toggle links 32 and 32' to the post 24 near the upper end thereof or just below the upper flange 23, the link 32' being 15 relatively short as compared with the length of its companion link 32 for a purpose presently described.

15 The link 32' is pivoted at 33 to a plate 34 on the thrust bar 26 some distance from the 20 inner and outer ends of the thrust bar and is also pivotally connected at 35 to the adjacent end of the link 32 to form a toggle joint, the upper end of the link 32 being pivoted at 36 to the post 24.

20 25 It will be observed upon reference to Figure 4 that each wing extends some distance above and below the horizontal plane of the pivotal connection 27 between the thrust bar 26 and post 24 thereby establishing a fulcrum 30 about which the wing is free to move particularly in case the lower edge of the scraper blade 12 of the wing should encounter a man-hole plate, a curb or other obstruction in the path of movement of the lower edge of the 35 wing when adjusted for use. That is, when the machine is in operation if the lower edge of the wing should engage a rigid obstruction it would be tilted inwardly and upwardly about the axis of the pivot 27 thereby causing 40 a corresponding upward and outward movement of the entire wing.

40 45 This upward and outward movement is permitted by the flexible connection 28 of the thrust bar 26 with the chassis of the vehicle and also by the flexing connection between the toggle links 32 and 32' in which case the thrust bar 26 will be moved upwardly and slightly outwardly while the links 32 and 32' will have a greater upward and outward movement by reason of the difference in leverage between the pivot 27 and lower and upper edges of the wing 8.

45 50 It will be observed, however, that as soon as the obstruction is passed the wing and also the thrust bar 26 and toggle links 32 and 32' will return to their normal positions by their own weight and by the impact of the snow against the wing until limited by the engagement of the shorter link 32' with the upper 55 face of the thrust bar 26, as shown by full lines in Figure 4.

Raising and lowering mechanism

55 60 Separate mechanisms are provided for adjusting the wings vertically independently

of each other and also for effecting an independent adjustment of the front and rear ends of each wing as may be required to vary the level of the snow operated upon and also for folding and unfolding the wings.

70 The means for raising and lowering the front end of each wing preferably consists of a chain 36 having its lower end attached to an eye 37 on the upper edge of the wing near the front end thereof and its upper end passed through a keyhole slot 38 in the upper end of the adjacent post 20, Figure 3, whereby the adjustment of different links in the opening 38 will effect a corresponding raising or lowering of the front end of the wing and will also hold the end of the wing in its adjusted position against downward movement while permitting its free upward movement.

75 80 The means for raising and lowering the rear end of each wing and also for effecting a bodily vertical movement thereof preferably consists of a conventional construction of chain or cable hoist having a lower and upper sheaves 39 and 40 attached respectively to the upper edge of the wing —8— 90 and to a suitable crane 41 and connected in the usual manner by a chain or cable 42 which is passed around the sheaves 39 and 40 and has one end attached to the frame of the sheave 40, the latter being operated by a hand chain or cable 43 through the medium of the usual power multiplying gears, not shown, but commonly used in hoisting devices of this character to permit the wing to be raised with a minimum power. The cranes 41, Figures 2 and 5, one for each wing are hinged at 44 to vertically spaced brackets 45 on separate upright posts 46 to swing in horizontally about parallel vertical axes, the posts 46 being secured by bolts 47 or equivalent fastening means to opposite sides of the box 4 approximately midway between the ends thereof and as nearly as possible midway between the opposite ends of their respective wings.

95 100 105 110 These posts extend some distance above the box 4 while the cranes 41 are pivotally attached to the posts or to the brackets 45 thereon some distance above the box to allow free vertical movement and upon lateral swinging of the wings along their respective guide bars 18 and also vertical angular movements about their respective pivots 16 from the positions shown in full lines to the positions shown by dotted lines in Figure 2.

115 120 125 The upper ends of the posts 46 are braced against forward and rearward vibration diagonal brace bars 48, Figure 2, and also braced against relative lateral vibration by additional diagonal brace bars 49, Figure 5.

The lower ends of the wing-supporting posts 20 are connected by a cross bar 50 having its ends secured by bolts 51 or equivalent fastening means to the posts, as shown more clearly in Figure 3.

In Figure 2 the box 4 is shown as supported upon a plurality of cross bars 52 which, in turn, are supported upon lengthwise bars 53 resting upon the upper edges of the sills 1 and secured thereto by any suitable fastening means, not shown.

Operation

- When the plow 5 and leveling wings 8 are 10 adjusted for use for the removal and leveling of the snow along the highway and the machine is propelled forwardly the wings 7 of the plow shall extend some distance beyond the opposite sides of the chassis of the vehicle 15 and remove and deflect the snow laterally from the pavement beyond opposite sides of the vehicle thereby forming a channel through the snow of substantially the transverse width of the plow so that the snow at 20 opposite sides of the channel will be accumulated in ridges or banks. Then, as the vehicle continues its forward movement the wings 8 shall extend some distance beyond the paths of travel of the outer edges of the plow blades 25 7 and remove and deflect outwardly the ridges or banks formed by the plow thereby greatly increasing the available width of the highway for traffic purposes and at the same time leveling off the snow in the path of the wings. 30 These successive operations of the plow 5 and wings 8 upon the snow not only conserve the power required for clearing the highway of snow over a maximum width most convenient for traffic purposes, but also reduce 35 the liability of redrifting of the snow into the channel formed by the plow thereby assuring a clear highway of sufficient width for the passage of traffic without material interference by the snow even though the latter may be of considerable depth.
- On the other hand, if the ridges or banks of snow at the sides of the channel formed by the plow 7 are excessively deep or sufficiently heavy to resist the power of the 45 motor to propel the machine forwardly the rear ends of the wings may be elevated or rocked upwardly by their respective hoisting devices 42 about the axes of their corresponding pivots 16 for the purpose of reducing such resistance or, if desired, the wings may be elevated bodily along their respective 50 guide rods 18 by the same hoisting devices and by the adjusting chains 36 to bring the lower edges of the wings varying distance 55 above the surface of the pavement parallel therewith or at an angle thereto according to the amount of adjustment of the hoisting devices 42 and 36.
- Furthermore when the use of the wings 8 60 is not required they may be drawn upwardly and inwardly along the guide rods 18 and about the axes of their pivots 16 until folded close to the adjacent sides of the body 4 or to the position shown by dotted lines in 65 Figure 2, it being understood that during this

upward and inward folding movement the thrust bars 26 and links 32 will also be rocked upwardly on their respective clevises 28 to assist in drawing the rear ends of the wings inwardly as the latter are elevated and also to partially support the wings in their elevated inwardly folded positions.

When the wings are folded to their inoperative positions as just described the supporting cables 36 for the front ends of the 70 wings may be drawn through their respective openings 38 to assist in holding said wings in their elevated positions.

When the wings are adjusted to their operative position for removing or leveling the 80 snow along the highway any obstacle which may be encountered by the lower edges of the wings would cause said wings to automatically rock upwardly and rearwardly thereby effecting a corresponding movement of the 85 toggle links 32 and 32' in a manner previously described, but under normal conditions the shorter links 32' will rest upon the upper edges of their respective thrust bars 26 so that the links 32 may serve as braces between the 90 thrust bars and posts 24 to firmly hold the wings in their operative positions except when encountering obstacles in the roadway as previously explained.

I claim:

1. In combination, a motor vehicle, a snow plow mounted on the front end of the vehicle, leveling wings having their front ends hingedly connected to opposite sides of the vehicle some distance to the rear of the plow for vertical and lateral swinging movements, opposite side posts secured to and extended upwardly from the vehicle between the front and rear ends of the leveling wings, cranes hingedly mounted on the posts to swing about vertical axes, and adjustable connections between the cranes and wings for swinging the latter vertically.
2. In combination, a motor vehicle, a snow plow mounted on the front end of the vehicle, leveling wings having their front ends hingedly connected to opposite sides of the vehicle some distance to the rear of the plow for vertical and lateral swinging movements, thrust-bars between the lower portions of the wings 105 and adjacent sides of the frame, and flexing connections between the thrust-bars and upper portions of the wings.
3. In combination, a motor vehicle, a snow plow mounted on the front end of the vehicle, leveling wings having their front ends hingedly connected to opposite sides of the vehicle some distance to the rear of the plow for vertical and lateral swinging movements, adjustable means for raising and lowering the 110 front ends of the wings, upright posts pivotally mounted on the wings to rock about vertical axes, thrust-bars having their inner ends operatively connected to the vehicle and their outer ends pivotally connected to the 115

lower portions of said posts, and flexing connections between the upper portions of the posts and adjacent thrust-bars.

4. In combination, a motor vehicle having a chassis frame, a snowplow mounted on the front end of the frame, a thrust-bar hingedly connected at its inner end to one side of the frame to extend outwardly therefrom, a snow-leveling wing having its front end hingedly connected to said frame to swing vertically and laterally and its rear portion pivotally connected to the outer end of the thrust-bar to tilt forwardly and rearwardly, a link pivoted to the thrust-bar and normally extended inwardly from its pivot against the upper face of the thrust-bar, and a brace-link having one end pivotally connected to the inner end of the first named link and its other end pivotally connected to the wing in a plane some 20 distance above the pivotal connection of the thrust-bar with the wing.

5. A snow leveling device as in claim 4 in which the chassis is provided with an upright post, a crane hinged to the post to swing about a vertical axis, and cable-and-sheave connections between the crane and wing for raising and lowering said wing.

In witness whereof I have hereunto set my hand this 11 day of April, 1929.

CARL H. FRINK.
